VIOLIN TUNER

Filed Sept. 30, 1927

Isaac Martyn
INVENTOR

UNITED STATES PATENT OFFICE.

ISAAC MARTYN, OF TULSA, OKLAHOMA.

VIOLIN TUNER.

Application filed September 30, 1927. Serial No. 223,172.

My invention relates to a supplemental tuning device for violins and is particularly adapted to overcome the well known difficulties experienced in properly tuning the E string of a violin. However, it will be understood that my invention can be utilized in tuning any string of a musical instrument if conditions encountered demand such use.

- 10 The purpose of my invention is to provide a device of the character specified which is simple in construction, cheap to produce, easily associated with a desired string and efficient in operation.
- 15 With the above and other purposes in view my invention consists in the details of construction and the arrangement and combination of parts to be hereinafter more fully described and particularly pointed out 20 in the appended claims.

In describing my invention in detail reference will be had to the accompanying drawing wherein like characters of reference denote corresponding parts in the 25 several views, and in which

Figure 1 is a detail perspective view of a fragment of a violin showing my invention operatively associated with its E string;

Figure 2, an enlarged detail perspective 30 view of my invention with a fragment of a violin string in operative association therewith;

Figure 3, a plan view of my invention as shown in Figures 1 and 2 with certain elements thereof shown in operative position in full lines and in inoperative position in dotted lines; and

Figure 4, a detail view of the string engaging plunger.

40 Referring to the drawing A indicates a violin including the usual string anchor 10, bridge 11 and strings 12.

By referring to Figures 2, 3 and 4 it will be seen that my improved tuning device embodies a U-shaped member B having arms 45 13, 14 and an arm connecting portion 15. The free ends of the arms 13 and 14 are formed to provide oppositely disposed lateral hooks 16 and 17 respectively in which the desired string to be tuned is adapted to 50 be engaged as clearly shown in Figures 1, 2 and 3. Disposed between the arms 13 and 14 is a string engaging plunger 18 having a

groove 19 in which the string being tuned is seated. The plunger 18 also includes 55 arms 20 and 21 which are slidably engaged in the arm connecting portion 15 of the member B. Threaded in the arm connection 15 between the arms 20 and 21 is a screw 22 which is operable to engage the 60 plunger 18 and force the latter against a string to be tuned which is seated in the hooks 16 and 17.

In operation it will be apparent that when the desired string is seated in the hooks 16 and 17 rotation of the screw 22 to the right 65 will bring one end of said screw into engagement with the plunger 18 and force the latter against the string. As movement of the string on opposite sides of the plunger is 70 resisted by the hooks 16 and 17 it will be apparent that the movement of said plunger will increase the tension of the string until the desired tension is imparted for proper tuning.

I claim:

1. A supplementary tuning device for violins comprising a U-shaped member having the free ends of its arms formed to provide oppositely disposed laterally opening 80 hooks adapted to receive a violin string to be tuned while the latter is anchored at both ends, and means carried by the member between its arms operable against a string while the latter is engaged against said 85 hooks.

2. A supplementary tuning device for violins comprising a U-shaped member having string engaging portions at the free ends of its arms, a string engaging plunger 90 slidably and non-rotatably mounted in the arm connecting portion of said member, and means for moving and holding said plunger against a string.

3. A supplementary tuning device for 95 violins comprising a U-shaped member having string engaging portions at the free ends of its arms, a string engaging plunger including spaced arms slidably engaged in the arm connecting portion of said member, and a screw threaded in the member between the arms of the plunger operable to move said plunger against a string while the latter is engaged against said string engaging portions.

ISAAC MARTYN.
